FUSE PULL-OUT DEVICE

Ralph A. Millermaster, Milwaukee, Wis., assignor
to Cutler-Hammer, Inc., Milwaukee, Wis., a corporation of Delaware

Application January 13, 1938, Serial No. 184,715

9 Claims. (Cl. 200—114)

This invention relates to improvements in fuse pull-out devices.

A primary object of the invention is to provide a combination main and range fuse pull-out device of novel form.

Another object is to provide a device of the character aforementioned, embodying main and range fuse carrying plugs, with means to insure against insertion of the range fuse carrying plug into the receptacle normally adapted to accommodate the main fuse carrying plug.

Another object is to provide a combination main and range fuse plug switching device of the character aforementioned wherein means, including the aforementioned means to insure against interchangeability of the range fuse plug, are provided for effecting "on" and "off" positioning of the fuse plugs within their respective receptacles.

Another object is to generally improve the details of construction of the parts of such fuse pull-out devices and the manner of supporting the same within the enclosing casing.

Another object is to provide a novel form of handle for such fuse plugs or pull-outs.

Another object is to provide novel means for facilitating wiring of such devices.

Another object is to provide a novel arrangement of branch circuit fuse receptacles for association with said main and range fuse pull-outs.

Other objects and advantages of the invention will hereinafter appear.

The accompanying drawings illustrate a preferred embodiment of the invention which will now be described—it being understood that the embodiment illustrated is susceptible of modification in respect of certain structural details without departing from the spirit and scope of the invention as defined by the appended claims.

In the drawings,

Figure 1 is a top plan view (half-scale) of a molded insulating base providing main and range fuse plug receptacles, and an associated insulating base providing receptacles for a plurality of branch circuit fuse plugs, the contact and wiring terminal elements being shown in assembled relation.

Fig. 2 is a bottom plan view of the parts shown in Fig. 1, illustrating the manner of attaching said parts to the base members, and the manner in which certain of said parts are electrically connected.

Fig. 3 is a top plan view of the "range fuse"

pull-out, which is adapted for insertion only in the receptacle at the right hand side of Fig. 1.

Fig. 4 is a bottom plan view of the pull-out shown in Fig. 3, illustrating the form and arrangement of the grooves or recesses which provide for "on" and "off" positioning thereof within the right hand recess of Fig. 1, and which also insure against operative positioning thereof within the left hand recess of Fig. 1.

Fig. 5 is a sectional view on the line 5—5 of Fig. 1, illustrating the manner of supporting the device within an enclosing casing of suitable form.

Fig. 6 is a fragmentary sectional view (full scale) on the line 6—6 of Fig. 5, the neutral bus member being omitted, and the range fuse plug being turned 180 degrees to limit the degree of insertion thereof, for "off" position.

Fig. 7 is a fragmentary top plan view of the enclosing casing, illustrating the manner of attaching the metal supporting plate for the insulating base members, and illustrating the form of the neutral bus member and the manner of attaching the same to the bottom wall of the casing.

Fig. 8 is a detail perspective view of a fragment of a bus member or conducting strip having my improved wiring terminal member or clamp rigidly attached thereto.

Fig. 9 is a fragmentary bottom plan view of a pull-out quite similar to that illustrated in Fig. 4, but showing the modified form of grooves or recesses to provide for "on" and "off" positioning thereof within the left hand recess in Fig. 1, and

Fig. 10 is a schematic and diagrammatic view illustrating the manner of effecting the circuit connections for the various elements of the complete device.

Referring to the drawings, the numeral 15 designates a base which is molded from a suitable insulating material, such as grey porcelain. Base 15 is provided in its front face with a pair of relatively large substantially rectangular recesses 16 and 17, the bottom walls of said recesses being respectively provided with openings or passages 18 and 19 similarly positioned adjacent to the four corners thereof. Located beneath the bottom walls of said recesses and aligned with the respective openings or passages are a corresponding number of stationary contacts 20 of like form. As best illustrated in Fig. 6, each stationary contact comprises a pair of upwardly extending resilient arms spaced slightly apart and having flared upper ends or edges 55

to facilitate insertion therebetween of the ends of contact prongs 21 of like form associated with the fuse pull-outs, as hereinafter described. The arms of contacts 20 are preferably formed from 5 suitable lengths of strip material, such as phosphor bronze, and said contacts are secured in position by bolts 22, the heads of which are positioned in countersunk recesses in the bottom walls of recesses 16 and 17, and nuts 23, which clamp 10 the contacts against ledges offset upwardly from the rear surface of base 15.

As best illustrated in Figs. 2 and 6 certain of 15 said bolts 22 and nuts 23 act to clamp their respectively associated contacts 20 in mechanical and electrical engagement with suitable copper bus members of different lengths, which are respectively numbered 24, 25, 26 and 27. As shown in Fig. 2, bus members 25 and 26 are electrically connected with each other through the medium 20 of a bus member 28, these parts being mechanically attached to the branch circuit fuse block 29, which is preferably molded separately from base 15, but of like material. The attaching means for these parts comprise bolts 30 and 31 25 of like form, the heads of which are adapted to form the center contacts of two of the branch circuit fuse sockets, as shown in Fig. 1, nuts being provided for said bolts, as shown in Fig. 2, to clamp the parts in assembled relation. Like 30 bolts 32 and 33 and their associated nuts act to clamp bus members 24 and 27 to block 29, the heads of said bolts providing center contacts for the other branch circuit fuse sockets, Fig. 1.

Bus members 24 and 27 are electrically connected by a bus member or strap 34 (Fig. 2) 35 which is retained in assembled position by a pair of bolts 35^a and 36^a, the heads of which are located in countersunk recesses in the bottom walls of recesses 17 and 16 (Fig. 1). The branch 40 circuit fuse sockets comprise screw shell contacts 35, which may be of usual form, each having a wiring terminal plate 36 and binding screw 37 associated therewith. As indicated in Figs. 2 and 5, the bus members 24 to 27 provide a substantial rigid mechanical connection between base 15 and block 29. Attached to base 15 at 45 the end of the latter remote from the branch circuit fuse sockets, as by means of a corresponding number of the bolts 22, are four relatively short bus members 38 of like form, as shown in Figs. 1, 2 and 5.

Each of the bus members 38 and bus members 25 and 27 has attached thereto a solderless wiring terminal device of the character best illustrated 55 in Fig. 8. As shown in this figure, each bus member has portions of its sides cut away to provide a head 39, and a neck 40 of a width and length corresponding rather closely to the internal width and the length, respectively, of a hollow metal member 41 of substantially rectangular form in cross section. Member 41 is 60 preferably formed by cutting or sawing the desired length thereof from a seamless steel tube of substantially rectangular form in cross section, as illustrated. One wall of member 41 is provided with a relatively large tapped opening to accommodate the threaded shank of a screw 42, the diameter of which shank is preferably only slightly less than the width of the rectangular 65 opening or passage through member 41, as best illustrated at the left hand side of Fig. 5. The head of each screw 42 is preferably of hexagonal or other polygonal contour, to provide for operation thereof by a suitable wrench, and the same is also preferably provided with a kerf to alter-

natively provide for operation thereof by a screw driver. The lower end of each screw shank is preferably flat, to provide a relatively large clamping area.

With reference to Fig. 8, it is to be understood 5 that member 41 is initially tilted in one direction or the other (with screw 42 omitted or sufficiently withdrawn to permit clearance for the head 39 at diagonally opposite sides of the opening in said member). Member 41 is then turned to upright 10 position, as shown in Fig. 8, and while the neck 40 is held against the inner surface of the lower wall of the opening in member 41, a pair of integral lugs, such as 43, are swaged or bent inwardly from opposite side edges of the bus member (such 15 as 38) into engagement with the exterior walls of member 41 and opposite ends 39^a of head 39 are swaged against the forward end of said member 41 to rigidly and permanently secure the latter to the bus member. The exposed surface of 20 neck 40 within member 41 is preferably provided with a series of grooves and ridges, or is otherwise roughened, to provide a gripping surface for the conductor or wire pressed thereagainst by tightening of the clamping screw 42. As will be understood, the flat lower end of the shank of screw 42 acts to clamp a conductor tightly and directly 25 against the copper bus member (such as 38); and hence both member 41 and screw 42 may be formed of steel, to insure proper strength and 30 durability of these parts. The solderless wiring terminal device shown in Fig. 8, including parts 38, 41 and 42, forms a portion of the subject matter of my copending application, Serial No. 261,527, filed March 13, 1939. 35

As best illustrated in Fig. 1 the recess 16 is provided on the longer sides thereof with a pair of integral alined ribs 44 and 45, said ribs extending from the bottom wall of said recess to a plane slightly above the upper edge of the side 40 walls of the recess, as shown at the right hand side of Fig. 6. With reference to Fig. 1, it will be noted that ribs 44 and 45 are located nearer to the upper end wall of recess 16 than to the lower end wall thereof, and that said ribs extend laterally into recess 16 to like degrees.

The range fuse carrying plug 46 (Figs. 3 and 4) is provided in its inner surface with recesses or depressions 47 and 48 to respectively register with and accommodate the upper end portions 50 of ribs 44 and 45, when said plug, in the relation shown in Fig. 3 is fully inserted into recess 16, Fig. 1, to the "On" position thereof illustrated in Fig. 5. Plug 46 is preferably provided with the legend "On," as shown at 49 to indicate 55 closed circuit positioning of plug 46 under these conditions—assuming insertion of the proper "range" capacity fuses (not shown) within the pairs of longitudinally alined cartridge type fuse holding clips 50, 50 and 50, 50 (Fig. 4). Each 60 clip 50 has associated therewith a contact prong 21 and said prongs and clips are attached to the insulating base of the plug 46 by means of bolts or screws 51 and nuts 52. 65

However, if plug 46 is turned through an angle of 180 degrees, from the position thereof shown in Fig. 3, the recesses 48, 47 in the inner surface thereof will not register with the respective ribs 44, 45, wherefore the inner surface portions 53 70 and 54 of said plug will rest upon the upper ends of ribs 44 and 45 to restrain the contact prongs from engagement with contacts 20, as shown at the right hand side of Fig. 6. Plug 46 is preferably provided with the legend "Off," as shown 75

at 55, which is located in indicating positioning under these conditions.

Referring again to Fig. 1, it will be noted that recess 17 is provided with a pair of ribs 56 and 57, which are alined with the ribs 44, 45. However, ribs 56, 57 extend laterally into recess 17 to a greater extent than the ribs 44, 45 extend into recess 16. Inasmuch as the recesses 47, 48 in the inner surface of plug 46 do not have a lateral depth sufficiently large to accommodate ribs 56, 57, it follows that the range fuse plug 46 cannot in either rotary position thereof be inserted into recess 17 to a degree sufficient to effect engagement of contact prongs 21 with the contacts 20 positioned below the bottom wall of said recess. This feature is of great practical importance, since it prevents accidental or careless insertion of the range fuse carrying plug 46 into circuit completing relation to the recess 17 which is intended 20 to recess only the "main" fuse carrying plug—a fragment of which is shown at 58 in Fig. 9—it being understood, of course, that the "range" fuses employed will have a substantially lower rating or current carrying capacity than the 25 "main" fuses.

With reference to Figs. 9 and 6, it is to be understood that fuse carrying plug 58 is substantially like plug 46 aforescribed, except that plug 58 is provided with recesses 59 and 60 of sufficient lateral depth to accommodate ribs 56 and 57, respectively, whereby plug 58 in one position thereof is insertable into recess 17 to a degree sufficient to effect engagement of contact prongs 21 with contacts 20, as shown at the left 35 hand side of Fig. 6.

It will be understood that main fuse plug 58 might be unintentionally inserted in a corresponding relation into circuit completing position with respect to the recess 16 for the range 40 fuse plug 46, but such unintentional insertion would not endanger the main fuses carried by plug 58. Moreover, under these conditions circuit could not be completed from the main line contacts associated with recess 17, due to the 45 aforescribed inability to insert the range fuse carrying plug 46 into circuit completing relation to said recess 17. The error would therefore require to be corrected as a prerequisite to completion of the circuit from the main lines or 50 source of current supply.

As shown at the left hand side of Fig. 6, the contact prongs 21 and fuse holding clips 50 are retained in assembled relation to plug 58 by means of screws or bolts 51 and nuts 52 like 55 those aforescribed. Due to the relatively high current carrying and controlling capacity of the fuses to be carried by plug 58, I prefer to interpose between the inner surface of plug 58 and each of the right angled portions of the contact 60 prongs 21 a fiber strip 59 of a width at least as great as the width of the respective prongs, the free ends of said fiber strips extending downwardly along the respective contact prongs 21, and being secured to the latter, as by means of 65 rivets or eyelets 60.

It follows that upon insertion or withdrawal of plug 58 with respect to recess 17 there is no possibility that the user's hands or fingers will 70 come in contact with the prongs 21 when current is passing through the latter. It is to be understood that after final assembly of the parts, the countersinks or recesses within which the various screw heads 22 and 51 are located will be filled with wax or other insulating sealing material to 75 provide a complete dead-front for the bottom

walls of recesses 16 and 17 and for the exposed surfaces of fuse carrying plugs 46 and 58.

Plugs 46 and 58 are provided with handles of novel form. Each handle comprises a rod or shaft 61 of square form in cross section, as shown 5 in dotted lines in Figs. 4 and 9, preferably formed of cold rolled steel. Said rods are insertable upwardly and slidably within centrally located passages of corresponding cross section formed in plugs 46 and 58. Each rod 61 is provided at 10 its lower end with an enlargement or head 62 which limits the upward movement thereof with respect to its associated plug. Each rod 61 is also provided at its upper end with cut-away portions at two opposite sides thereof to provide an 15 extension of rectangular cross section, but of reduced width—as shown in dotted lines at 63 in Fig. 5—to fit within an opening of corresponding shape provided in the flat metal finger grip member 64, and said extension is then split, 20 swaged or upset over the upper surface of member 64, as shown at 65, to rigidly attach said members to each other. During assembly of the handle parts a coiled compression spring 66 is 25 interposed between the lower surface of member 64 and the upper surface of the respective plug 46 or 58, whereby member 64 is normally biased to its upper extreme position, as shown in Fig. 5 and at the left hand side of Fig. 6.

As shown in Figs. 5 and 6 the metal casing or 30 box 67 is provided with a cover 68 which is removably attached thereto as by means of screws 69, cover 68 having an opening 70 of a size and contour to accommodate only the upper end portions of insulating bases or blocks 15 and 35 29. An auxiliary cover member 71 is hinged to cover 68 as shown at 72, and suitable means, such as a coiled torsion spring (not shown) may be provided to bias auxiliary cover member 71 to open position. Member 71 is provided with an 40 opening 73 (Fig. 5) to accommodate the manually releasable spring latch member 74. Member 71 is preferably provided with an integral loop 75 and member 74 is provided with an opening (not shown) to accommodate the usual wire, the 45 ends of which may be sealed together, for the purpose of sealing member 71 in closed position.

The auxiliary cover member 71 is preferably bulged outwardly as shown, to provide clearance for the rod 61 and member 64 when the fuse 50 carrying plug is in circuit completing position, as illustrated at the left hand side of Fig. 6, and to likewise provide clearance for rod 61, member 64 and a portion of the fuse carrying block, such as 46, when the latter is out of circuit completing 55 position, or in "Off" position as shown at the right hand side of Fig. 6.

The aforementioned block 15 is attached to a flat sheet metal plate 76 (Figs. 5 to 7) as by means of four screws 77 the heads of which are 60 located in recesses 78 and the threaded shanks of which penetrate somewhat elliptical passages 79 provided in said block, and take into tapped openings 80 provided in plate 76. Block 29 is attached to plate 76 by screws like 77, the heads 65 of which are located in recesses 81 (Fig. 1) and the threaded shanks of which penetrate the somewhat elliptical passages 82 and take into tapped openings 83 provided in plate 76 (Fig. 7).

As shown in Fig. 7, casing 67 is provided on 70 its opposed long sides with brackets 84 having notches 85. Plate 76 is provided at two opposite corners thereof with sheared and bent portions to provide lugs or fingers 86 and 87 which are offset downwardly from the plane of said plate. 75

By initially tilting plate 76 lugs 86 and 87 may be inserted through notches 85 to afford a proper support for one end of the plate upon movement of the latter to its normal position. Rigidly attached to the bottom wall of casing 67 and underlying plate 76 adjacent to the other end of the latter is a hollow internally threaded member 88, a screw 89 (Figs. 5 and 7) penetrating an opening in plate 76 and taking into threaded member 88 to rigidly attach said plate 76 in assembled relation to, but spaced upwardly from the bottom wall of, the casing 67. A lock washer 90 is preferably interposed between the head of screw 89 and plate 76.

15 A neutral or grounded bus member 91 (Fig. 7) is secured to bosses 92 and 93 upon the bottom wall of casing 67, as by means of screws or bolts 94 and 95. Bus member 91 has a plate 96 attached thereto, as by means of rivets 97, and plate 96 carries four wiring terminal screws 98, each associated with one of the branch circuits; the other wiring terminal screw of each branch circuit being shown at 37 (Figs. 1 and 10). Attached to bus member 91 at the opposite end 25 thereof are three terminals or wiring clamping devices 41, 42 of the character aforescribed, the same being carried by relatively short bus members 99, 100 and 101, as illustrated. Plate 16 (Fig. 7) is cut away as shown at 102 to provide 30 access to the terminals last mentioned, and at 103 to provide access to terminal screws 98.

An arrangement of circuits to be controlled by the present device is illustrated diagrammatically in Fig. 10, wherein lines L¹, L² and L³ represent the source of current supply, and l¹, l² and l³ represent the lines leading to an electric range or similar translating device. Assuming "on" positioning of the main and range fuse plugs, with the main and range fuses M and R 40 respectively carried thereby, circuit may be traced from line L¹, by bus 38 through one of the main fuses M to bus 24, bus 34, and bus 27 through one of the range fuses R, and to line l¹; and from line L³ by bus 38 through the other 45 main fuse M, by bus 25, bus 28 and bus 26 through the other range fuse R, and to line l³; the neutral lines L², l² being jointly connected to the neutral or grounded bus member 91 aforescribed.

In Fig. 10, the numerals 104, 105, 106 and 107 50 designate branch lighting circuits or the like; circuits 104 and 107 being electrically connected through their respective branch circuit fuses and one of the main fuses M with line L¹, and circuits 105 and 106 being electrically connected 55 through their respective branch circuit fuses and the other main fuse M with line L³, and each of said branch lighting circuits being electrically connected with neutral bus member 91 and line L². Numerals 108 and 109 designate bus leads 60 electrically connected respectively with lines L¹ and L³ through the respective main fuses. Thus if the main fuses M are of 60 ampere capacity, and the range fuses R are of 30 ampere capacity, the bus leads may be utilized to provide a tap 65 up to 60 amperes capacity, with solderless terminal devices 41, 42 (Fig. 1), for serving either a water heater or an extra distribution fuse circuit panel, located remote from the combination entrance (or main) and range switch device 70 closed herein.

As shown in Figs. 3 and 4 the fuse carrying plug 46 (and also the fuse carrying plug 58 of Figs. 6 and 9) is provided with sets of openings or passages 110, 111 and 112, 113 to provide for 75 insertion of wire ends or rods into engagement

with the respective fuse holding clips of each pair, whereby the range and main fuses may be tested without requiring removal thereof from circuit. The block 29 (Fig. 1) carrying the branch circuit fuses is provided with four grooves or slots 114 5 to provide for testing of the branch fuses without removal thereof from their respective circuits, the terminals 36 or screws 37 being utilized for contact by one of the testing wires or rods when testing the branch circuit fuses. 10

If branch circuit fuses are not required or desired, the block 29 may be omitted, and relatively shorter bus members may be substituted for those shown at 24, 25, 26 and 27 in Fig. 2, thus permitting use of a casing substantially shorter than that shown at 67 (Fig. 5). Casing 67 may be provided with any desired number or form of knock-outs in the bottom, side and end walls thereof, several knock-outs 115 of well known form being shown at 115 in Fig. 7. 15

Each plug member 46 and 58 is provided in its upper surface with a recess 46^a (Figs. 3 and 5) to accommodate spring 66, when compressed, and finger grip member 64 in a relation substantially flush with said upper surface (see the right hand 25 side of Fig. 6). Recess 46^a also facilitates insertion of the finger or fingers between member 64 and the upper surface of the plug member, as best illustrated in Fig. 5. 20

What I claim as new and desire to secure by 30 Letters Patent is:

1. In a fuse carrying switch plug, in combination, a molded insulating plug member having a centrally located opening of polygonal cross section formed therein, a metal member of corresponding cross sectional contour penetrating said opening and slideable with respect thereto, said metal member having an enlargement at its lower end to limit the degree of upward movement thereof, said metal member having a finger grip 40 member rigidly and non-rotatably attached to the upper end thereof, and a coiled compression spring interposed between the upper surface of said insulating member and said finger grip member to normally project the latter to its upper 45 extreme position, said spring permitting depression of said metal member and said finger grip member upon closure of a suitable cover member associated therewith.

2. In a fuse carrying switch plug, in combination, a molded insulating plug member having a centrally located opening of polygonal cross section formed therein, a metal member of corresponding cross sectional contour penetrating said opening and slideable with respect thereto, said metal member having an enlargement at its lower end to limit the degree of upward movement thereof, said metal member having a finger grip member rigidly and non-rotatably attached to the upper end thereof, a coiled compression spring interposed between the upper surface of said insulating member and said finger grip member to normally project the latter to its upper extreme position, said spring permitting depression of said metal member and said finger grip member upon closure of a suitable cover member associated therewith, and said insulating member having a recess to accommodate said spring when compressed and said finger grip member in a relation substantially flush with the upper 70 surface of said insulating member.

3. In a fuse carrying switch plug, in combination, a molded insulating plug member of substantially rectangular contour, said plug member having a centrally located passage of square 75

therewith to provide for attachment of circuit wires thereto prior to insertion of said base into said casing, said base having a metal plate rigidly attached to the lower surface thereof, means including metal brackets located within said casing and attached to opposite side walls of the latter for supporting said metal plate in upwardly spaced relation to said bottom wall, and said means including a single screw adapted to 10 retain said metal plate in or release the same from assembled relation to said casing.

9. In a device of the character described, in combination, a metal casing having bottom, side and end walls, a flat metal plate supported in upwardly spaced relation to said bottom wall, means comprising a single screw adapted upon release thereof to permit removal of said plate from said casing, a molded insulating base rigidly but removably attached to said plate. said

base having a pair of substantially rectangular recesses formed therein and opening to the upper surface thereof, a main fuse carrying plug and a range fuse carrying plug insertable into the respective recesses in either an "on" or an "off" 5 position, the fuse carrying elements of said plugs being concealed in each of said positions, one of said recesses being so formed with respect to the range fuse carrying plug as to insure against insertion of the latter into an "on" position 10 within the former, a cover member rigidly and normally immovably attached to said casing and having an opening to provide for exposure of the recesses aforementioned, and an auxiliary cover member hinged to said cover member first 15 mentioned and adapted when closed to overlie said recesses.

RALPH A. MILLERMASTER.
